(57) **CLAIM**

The ornamental design for amplifier case with moderate flanges, as shown and described.

DESCRIPTION

FIG. 1 is a top, front, and left side isometric view of an amplifier case with flanges, showing my design.

FIG. 2 is a top view thereof.

FIG. 3 is a bottom view thereof.

FIG. 4 is a right side view thereof, the left side view being identical thereto.

FIG. 5 is a front view thereof; and,

FIG. 6 is a rear view thereof.
